UNITED STATES PATENT OFFICE.

FRED R. HARRIS, OF NEW YORK, N. Y., ASSIGNOR TO THE AMERICAN TOBACCO COMPANY,
OF NEW YORK, N. Y., A CORPORATION OF NEW JERSEY.

BOX-COVERING MACHINE.

No. 904,426.

Specification of Letters Patent. Patented Nov. 17, 1908.

Application filed July 20, 1904. Serial No. 217,306.

To all whom it may concern:

Be it known that I, FRED R. HARRIS, a citizen of the United States, residing at New York city, county of New York, and State of New York, have invented certain new and useful Improvements in Box-Covering Machines; fully described and represented in the following specification and the accompanying drawings, forming a part of the same.

This invention relates to machines for covering boxes and more particularly to machines for applying a covering sheet or strip of suitable material to the bottom and top 15 of a box and about the hinge side thereof.

In some cases the covering material so applied may serve to secure the body and cover portions of the box together and to form the hinge.

The invention has been made particularly with the idea of covering and hinging together the cover and body portions of boxes, the cover and body portions of which are each provided with side flanges, the side 25 flanges of the cover portion of the box extending outside of the side flanges of the body portion of the box. It will be understood, however, that the invention may be used for covering and hinging together the 30 cover and body portions of boxes of other forms.

A full understanding of the invention can best be given by a detailed description of a preferred construction embodying the various features thereof, and such a description will now be given in connection with the accompanying drawings showing such a preferred construction for covering boxes of the form above referred to.

In said drawings:—Figure 1 is a side view of such a machine. Fig. 2 is a plan view of the same. Fig. 3 is an end view looking in the direction of the arrow 3 of Fig. 1 and showing the frame partly in section. Fig. 4 is an enlarged plan view of a portion of the machine with parts removed. Fig. 5 is a longitudinal sectional view taken on line 5 of Fig. 2 on the scale of Fig. 4. Fig. 6 is a longitudinal sectional view of the covering 50 strip feeding and pasting mechanism, on a larger scale than Figs. 4 and 5. Fig. 7 is a view taken on line 7 of Fig. 6. Fig. 8 is a detail view, partly in section of the covering devices looking in the direction of the arrow 55 8 of Fig. 2. Fig. 9 is a similar view taken at

right angles to Fig. 8. Fig. 10 is a detail view of parts shown in Fig. 8, showing the same in a different position. Fig. 11 is a view taken at right angles to Fig. 10 and showing parts omitted from Fig. 10, and 60 Fig. 12 is a cross sectional view of the box as covered by the machine.

The covering sheets or strips are preferably cut from a web or continuous strip which is fed from a roll and pasted as it is 65 advanced to the cutting mechanism. Any suitable means may be employed for so feeding, pasting and severing the strip of covering material. As shown the strip α is drawn from a web roll supported on a shaft carried 70 by suitable hangers 10 by means of a pair of feeding rolls 11, from which it passes between a pasting roll 12 and a supporting and pressing roll 13. The pasting roll 12 is supplied with paste from a fountain 15, the 75 roll being mounted in bracket arms extending from the fountain so as to rotate past the outlet opening of the fountain, and a plate 16 adjustable toward and from the pasting roll is provided for regulating the thickness 80 of the layer of paste carried forward by the pasting roll. An adjustable scraper 17 is also provided for cleaning the surface of the pasting roll as it returns to take paste from the fountain. The pressing roll 13 is mounted 85 to move toward and from the pasting roll, as by being journaled in a frame 18 mounted to slide in ways 19, and is held in operative position under yielding pressure by means of a spring 20 acting to press the frame 18 90 upward toward the pasting roll. A thumb nut 21 on a rod extending downward from the frame 18 serves as a stop to limit the upward movement of the frame and pressing roll, and by turning the thumb nut the position to which the roll may be pressed toward the pasting roll by the spring may be adjusted. To permit the pasting roll to be raised, as for the purpose of threading or 95 drawing the strip between the pasting roll and the supporting roll, the fountain is preferably mounted to slide in vertical ways 25 and is supported by rods 26 pivotally connected to the sides of the fountain and having their lower ends provided with or connected to rings on eccentrics on a shaft extending beneath the fountain and provided at one end, as shown in Fig. 7, with means whereby it may be turned by hand for raising or lowering the fountain and pasting 100 105 110

roll when desired. Spring fingers 28 are preferably provided for bearing against the face of the pasting roll to insure the strip leaving the roll as it advances beyond the 5 pressing roll.

The pasting roll and the supporting roll are geared to turn together by means of gears 30 and 31 respectively on the shafts of said rolls, and are continuously driven by 10 means of a pinion 32 which meshes with a gear 33 on the shaft of the pasting roll, said pinion being driven from the cam shaft 35 by means of a sprocket chain 36. The feeding rolls 11 are geared to turn together and 15 are continuously driven by means of a sprocket chain 37 from the shaft of the pressing roll 13.

After leaving the pasting rolls the strip passes over a supporting plate or guideway 20 38 from which the end of the strip is drawn past the severing means and the severed portions then advanced to the covering means. As the strip is drawn over the support 38 intermittently and is fed from the pasting 25 rolls continuously, the support 38 is preferably placed some distance beyond the pasting rolls so as to allow the portion of the strip between the support and the pasting roll to fall in a loop during the intermissions 30 between its movement over the support. Strip feeding, pasting and severing means comprising means for continuously feeding and pasting the strip, a support beyond the pasting means, and means for advancing the 35 end of the strip intermittently over the support and past severing means is described and claimed in my application No. 182,569, filed November 25, 1903.

Any suitable severing means may be provided. The preferred means shown comprises a stationary lower blade 40 and a movable upper blade 41 which is preferably pivoted on one of a pair of guide rods 42, 43, and is oscillated intermittently by means 45 of a lever 44 connected by a rod 45 with an arm 46 mounted to oscillate with the knife blade, said lever 44 carrying a cam roll which runs in a cam groove 47 in the face of a cam disk 48 on the shaft 35. A wiper 50 49 is preferably provided lying above the path of the covering strip to wipe the face of the blade 41 as it rises after making its severing movement.

For drawing the end of the strip of covering material between the knives and then advancing the severed portion to the covering means, a pair of surface grippers 50 are preferably provided, said grippers being carried by a sliding frame or carriage 51 mounted to slide on the guide rods 42 and 43 and reciprocated to give the grippers their feeding and return movements by means of a lever 52, the lower end of said lever being connected by a rod 53 with one arm of a lever 54 the other arm of which carries a

cam roll running in a cam groove in the face of a cam disk 56 on the shaft 35. The grippers 50 are carried by rods extending from a shaft 57 journaled in bearings on the carriage 51. Springs 58 on the shaft 57 70 tend to rotate the shaft to raise the grippers, and the grippers are thereby normally held in the slightly raised position shown in Fig. 8, the rotation of the shaft and upward movement of the grippers being limited by 75 adjustable stops 59 which are engaged by lugs 60 extending from collars on the shaft 57. The grippers being in this normal raised position as the carriage makes its return movement to carry the grippers into 80 gripping position, the grippers will lie slightly above the support 38 so that they may be moved over the end of the covering strip lying on the support without engaging therewith. As the carriage reaches the end 85 of its return movement after the grippers have been advanced over the end of the support 38, downwardly extending lugs 61 on the collars on the shaft 57 engage adjustable abutments 62 whereby the shaft is 90 rocked against the tension of the springs 58 to throw the grippers down into contact with the pasted surface of the end of the covering strip, as shown by dotted lines in Fig. 8. The carriage and grippers then 95 start on their feeding movement to the right in Fig. 8, and the end of the strip is thereby drawn between the severing knives. When a sufficient length of the covering strip for 100 covering a box has been drawn beyond the severing knives, the gripper carriage is momentarily stopped while the severing blade 41 is actuated to sever the strip. The carriage then completes its forward or feeding movement to carry the severed portion of 105 the strip into position with relation to the covering means.

It will be noticed, that the surface contact grippers 50 which depend on the adhesion of their gripping faces to the pasted surface of 110 the covering strip, form a non-positive feeding means which permits of a slip between the grippers and the strip if the movement of the strip is resisted. It is often desirable that the covering material to be applied to 115 the boxes shall be printed or otherwise provided with suitable lettering or other matter for forming labels or with suitable decorative matter, and when the continuous strip of covering material is printed so that successive portions thereof bear the printed matter of successive covering sheets, it is necessary that successive sheets shall be cut from the strip to correspond with the matter printed thereon. To secure this result I 120 make use of a non-positive feeding means, such as the surface engaging grippers 50, and provide means for engaging registering devices on the strip to limit the movement of the strip by the grippers. Such registering 125 devices may be of any suitable form, such as 130

devices are preferably formed by a succession of perforations formed at intervals in the strip corresponding to successive sheet lengths to be severed from the strip. Perforations of a suitable form are shown at x' in Fig. 4. To coöperate with such perforations to determine the extent of movement of the strip at each feeding movement of the grippers 50, a pin 65 is provided projecting slightly above the surface of the support 38 and a presser, formed preferably by a flanged roll 66 carried by a pivoted arm 67 on a rock shaft 68, is provided for pressing the covering material against the pin. Such arm and pressing roll are normally held in operative position with the roll bearing yieldingly against the strip of covering material on the support 38 and over the pin 65 by means of a spring 69 on the shaft 68. The shaft 68 also carries a rod 70 extending toward the gripper carriage 51 in position to be engaged by a lug 71 carried by the gripper carriage before the carriage reaches the end of its return movement, whereby the pressing roll 66 is raised as the rod 70 is depressed by the lug 71 and is held in its raised position during the remainder of the return movement of the gripper carriage and during the first part of its feeding movement. Then when the gripper carriage has made a portion of its feeding movement the roll 66 is again allowed to press the strip lightly against the pin 65 so that when the strip has been moved a distance to bring another of the perforations x' to the pin 65 the pin will be caused to project through such opening and the movement of the strip stopped, the grippers thereafter slipping on the strip during any further movement they may have before coming to rest for the operation of the severing blades. As the grippers again come into gripping position, the pushing roll 66 is again raised from the strip of material to permit it to be drawn forward another sheet length by the grippers. It will be seen that by providing such interrupting means in combination with the non-positive feeding means, and by giving the grippers a slightly greater movement before the rest for the operation of the severing means than is necessary to feed a sheet length of the covering strip, the successive covering sheets will always be cut accurately between the labels on the strip.

For holding the strip of covering material flat on the support 38 a number of pressing fingers 72 are preferably provided, as shown in Figs. 2 and 5.

The boxes to be covered are supplied to the machine with the body portions and cover portions of the boxes associated together and ready to have the covering sheets applied to the bottom and top and about one side thereof. The boxes are placed in a holder 75 through which they are advanced

flatwise on edge by means of belts 76 mounted on vertical rolls 77 and 78 having their inner or feed runs extending inside the opposite side walls of the holder. For pressing the inner runs of the feed belts 76 inward and adjusting the pressure on the boxes, pressing rolls 79 are provided as shown in Figs. 2 and 3, such rolls being preferably carried by arms pivoted on the shafts of the rolls 77 and 78 and adjustable by means of adjusting screws 80. The belt rolls 77 are geared together, as shown in Fig. 2, and the shaft of one of said rolls is extended downward and driven by bevel gears 81 from a short shaft 82, which is driven by a sprocket chain 83 from the main driving shaft 85. The row of boxes in the holder is constantly pressed forward by the belts 76 to carry the end box of the row against the front plate 86 of the holder, and from this position the successive end boxes are fed edgewise downward by means of a plunger 87. The holder is preferably provided with a yielding bottom at the delivery end of the holder, such portion of the bottom of the holder being formed by means of a pivoted plate 88 normally held in supporting position by means of springs 89, as shown in Fig. 1, and adapted to turn downward to the position shown in dotted lines in Fig. 9 as the end box is forced downward from the holder. The plunger 87 is reciprocated by means of a lever 90 carried by a rock shaft 91 which shaft also carries an arm 92 connected by a link 93 with a lever 94 which carries a cam roll running in a cam groove in one face of the cam disk 56 on the shaft 35.

When the box bodies and covers are provided with covering material about the sides thereof the edges of which are turned over against the top and bottom, said turned over edges are liable to become displaced or injured by the movement of the end box against the next box in the holder as it is pushed downward by the plunger 87. To avoid this difficulty there is preferably provided means whereby, as the plunger makes its downward movement to push the end box out of the holder, the next box will be moved slightly backward in the holder away from the end box so that the surfaces of the two boxes will not be in contact as the end box is moved from the holder. For this purpose the plunger 87 is preferably provided with a rearward extension 95 having a beveled or wedge shaped lower end for engaging the next to the last box in the holder to push the same back slightly in the holder as the plunger moves downward to advance the end box from the holder. The wedge extension 95 is preferably and as shown in Fig. 8, of less width than the plunger. The next to the last box in the holder will thus be forced slightly backward and out of contact with

the end box in the holder as the latter is moved edgewise from the holder, and all danger of injury to the boxes by reason of one sliding against the other is thereby 5 avoided.

The covering sheets are carried by the grippers 50 into position beneath the end of the box holder so that the central portion of the blank will lie directly beneath the end box in the holder. The plunger 87 makes its downward feeding movement after the covering blank has been carried into position and thereby forces the end box in the holder downward to carry the lower edge or side of 10 the box against the covering blank and to force the box and covering blank downward between a pair of folding and pressing rollers 100 whereby the blank is folded upward and pressed against the top and bottom of 15 the box. A second pair of rollers 101 is preferably provided beneath the rollers 100 for further pressing the covering material against the top and bottom of the box as the box is moved downward between said rollers. 20

25 To avoid the necessity of having the plunger 87 make such a long feeding movement as would be required to move the box between and clear of the pressing rolls, other feeding means are preferably provided for 30 engaging the box after it has been forced between the folding rolls and for moving it the remainder of the distance to carry it clear of said rolls. The plunger is preferably given a reciprocation sufficient to carry the upper 35 edge of the box below the plane in which the covering blanks are fed and supported by the feeding grippers 50. For completing the movement of the box between the folding and pressing rollers 100 and 101, a pair of 40 feeding arms 102 is preferably provided having inwardly extending ends or shoulders 103 adapted to project over and engage the upper edge of the box which has been pushed downward between the rolls by the plunger, 45 such feeding arms being preferably pivotally mounted in a reciprocating support 104 which support is preferably mounted to slide vertically in ways 105 and reciprocated by means of a lever 106 which carries a cam roll 50 running in a cam groove in one face of a cam disk 109 on the shaft 35. The feeding arms 102 are normally thrown outward to the non-operative position shown in Fig. 8 by means of springs 107 acting on rods 108 55 extending upward from inwardly extending ends of said arms, as shown in Fig. 8, and said feeding arms are thrown inward against the pressure of the springs 107 by means of a presser bar 110 which is adapted to engage 60 the upper ends of the rods 108 and force the rods downward, thereby swinging the feeding arms inward. The presser bar 110 is carried by a rod 111 mounted to slide vertically in the support 104 and normally stands in 65 position with relation to the support 104 as

shown in Fig. 8, being held in position preferably by means of a friction spring 112.

As the plunger 87 moves downward, the support 104, feeding arms 102 and presser bar 110 stand in the position shown in Fig. 70 8, and a covering blank has been carried into position by the grippers 50, as shown in said figure. As the end box in the holder is pushed downward from the holder by the plunger, the bottom edge or side of the box 75 engages the central portion of the covering sheet and carries it down against the presser bar 110, as indicated by dotted lines in Fig. 9. The downward movement of the plunger then continuing, the box is pushed downward between the folding and pressing rolls 100 and the pressing rolls 101, the presser bar being forced downward by the box while the support 104 remains stationary; and the downward movement of the plunger continues until the box and presser bar are in the position with relation to the support 104 and folding and pressing rolls shown in 80 Figs. 10 and 11. The extending portions of the covering sheet are thereby folded upward against the top and bottom of the box, and as the presser bar approaches the support 104 it engages the upwardly projecting ends of the rods 108, thereby forcing said rods 85 downward whereby the feeding arms 102 are swung inward to the position shown in Fig. 10 to carry their inwardly extending ends 103 over the upper edge of the box. The support 104 is then moved downward to the 90 position shown in Fig. 5, thereby drawing the box down between and clear of the pressing rolls, the plunger 87 meanwhile being returned to the position shown in Fig. 5 to permit another covering sheet to be carried 95 into position by the feeding grippers 50, and to permit the next box in the holder to be advanced into position to be fed downwardly by the next downward movement of the plunger. By its passage between the 100 folding and pressing rolls 100 and 101, the covering sheet will be pressed smoothly against the top and bottom of the box, and the portion of the sheet extending about the lower side of the box will be pressed firmly 105 against such side by means of the presser bar 110. It will be noticed that the pressure of the presser bar 110 against the lower side of the box is increased by the resistance of the spring pressed bars 108, and such resistance may be adjusted to give the desired 110 pressure on the portion of the covering sheet secured to such side of the box. The application of the covering sheet to the box being thus completed, the box is delivered 115 preferably by means of a horizontally reciprocating plunger 115 carried by a rod 120 116 in position to engage the covered box as it is supported by the feeding arms and presser bar and force it flatwise therefrom 125 and into a delivery chute 117 from which 130

the box may be taken by hand or received by suitable receiving devices.

The box having been delivered to the delivery chute 117 by the plunger 115, and the 5 delivery plunger having been retracted to the position shown in Fig. 3, the presser bar 110 is then moved upward with relation to the support 104 to the position shown in Figs. 8 and 9, and the support is then moved 10 upward to raise the feeding arms and the presser bar to the position shown in Figs. 8 and 9, the feeding arms having been returned to their outward position by the springs 107 when the rods 108 were released by the 15 upward movement of the presser bar. For moving the presser bar upward with relation to the support 104, a push lever 118 is preferably provided for engaging the downwardly projecting end of the rod 111, said 20 lever being connected by a link 119 with a lever 120 which carries a cam roll running in a cam groove in the face of the cam disk 109 on the shaft 35. The delivery plunger 115 is reciprocated by means of a lever 121 carried by a rock shaft which also carries 25 an arm 122 connected by a link 123 with a lever 124 which carries a cam roll running in a cam groove in the face of the cam disk 48 on the shaft 35.

30 The operation of the machine as a whole will be understood from the foregoing description and need not be further described.

It will be understood that the invention is not to be limited to the exact construction 35 and arrangement of parts shown and to which the foregoing description has been mainly confined, but that it includes changes and modifications thereof within the claims. It will be understood also that features of 40 the invention as claimed may be used independently of other parts shown or in combination with other co-acting parts or in other machines.

What is claimed is:—

45 1. In a machine for pasting a sheet of covering material to the hinge side and to the top and bottom of associated box bodies and covers, the combination of folding devices for folding the sheet against the top and bottom of the box, means for advancing a succession of associated box bodies and covers edgewise to the folding devices, means for supporting a pasted covering sheet in position to have an intermediate portion thereof engaged by the hinged side of the box as the box is advanced to the folding devices by said advancing means, and means for moving the boxes edgewise between the folding devices, to fold the extending portions of the wrapper against the top and bottom of the box, substantially as described.

50 2. In a machine for pasting a sheet of covering material to the hinge side and to the top and bottom of associated box bodies and

covers, the combination of folding devices for folding the sheet against the top and bottom of the box, means for advancing a row of associated box bodies and covers flatwise, means for advancing the end boxes of 70 the row successively to the folding devices edgewise, means for supporting a pasted covering sheet in position to have an intermediate portion thereof engaged by the hinged side of the box as the box is advanced 75 to the folding devices by said advancing means, and means for moving the boxes edgewise between the folding devices, to fold the extending portions of the wrapper against the top and bottom of the box substantially as described.

3. In a machine for pasting a sheet of covering material to the hinge side and to the top and bottom of associated box bodies and covers, the combination of folding devices 85 for folding the sheet against the top and bottom of the box, a reciprocating pusher for advancing successive associated box bodies and covers edgewise to and between the folding devices, means for supporting pasted 90 covering sheets in position to have an intermediate portion thereof engaged by the hinged side of the boxes as the latter are advanced to the folding devices by said pusher, and means for completing the movement of the boxes between the folding devices, to fold the extending portions of the wrapper against the top and bottom of the box substantially as described.

4. The combination of folding devices for 100 folding a covering sheet against opposite sides of an article, means for advancing a succession of articles to and between the folding devices, means for supporting the covering sheets in position to have an intermediate portion thereof engaged by the articles as they are advanced to the folding devices by said advancing means, and means for completing the movement of the articles 105 between the folding devices to fold the extending portions of the wrapper against the sides of the article, substantially as described.

5. In a machine for pasting a sheet of covering material to the hinged side and to the top and bottom of associated box bodies and covers, the combination of folding devices for folding the sheet against the top and bottom of the box, means for advancing a succession of associated box bodies and covers edgewise to the folding devices, means for supporting a covering sheet in position to have an intermediate portion thereof engaged by the hinged side of the box as the box is advanced to the folding devices by said advancing means, and means adapted 115 to be projected from the far side of the folding devices to engage the boxes which have been advanced by said advancing means and to move the boxes edgewise between the folding devices, substantially as described.

6. The combination of folding devices for folding a covering sheet against opposite sides of an article, means for advancing a succession of articles toward the folding devices in the direction of their movement between the folding devices, a member mounted to reciprocate on the opposite side of the folding devices from said advancing means, a feeding arm extending from said member 10 for engaging the successive articles to move them between the folding devices, and means for supporting the covering sheets in position to have an intermediate portion thereof engaged by the articles as the latter are advanced to the folding devices, substantially as described.

7. The combination of folding devices for folding a covering sheet against opposite sides of an article, means for advancing a 20 succession of articles toward and between the folding devices, sheet feeding means for advancing a succession of covering sheets into position to have an intermediate portion thereof engaged by the articles as they are advanced to the folding devices, a member mounted to reciprocate on the opposite side of the folding devices from said advancing means, and a feeding arm extending from said member for engaging the successive articles 25 to complete the movement of the articles between the folding devices, substantially as described.

8. The combination with folding devices for folding a covering sheet against opposite sides of an article, of a reciprocating plunger 87 for advancing the article to and between the folding devices, means for supporting a covering sheet in position to have an intermediate portion thereof engaged by 35 the article as it is advanced to the folding devices, and a pair of reciprocating feeding arms 102 for engaging the article and completing the movement of the same between the folding devices, substantially as described.

9. The combination with folding devices for folding a covering sheet against opposite sides of an article, of a reciprocating plunger 87 for advancing the article to and 40 between the folding devices, means for supporting a covering sheet in position to have an intermediate portion thereof engaged by the article as it is advanced to the folding devices, a pair of reciprocating feeding arms 102 for engaging the article and completing the movement of the same between the folding devices, and means for delivering the articles from the feeding arms transversely to the direction of movement of the feeding 45 arms, substantially as described.

10. The combination with folding devices for folding a covering sheet against opposite sides of an article, of means for advancing the article toward and between the folding

devices, a reciprocating support, a pair of 5 pivoted feeding arms 102 carried by said support for completing the movement of the article between the folding devices, and means controlled by the movement of the article for throwing said feeding arms into 70 position to engage the box, substantially as described.

11. The combination with a folding device for folding a covering sheet about an article, of means for advancing the article to the 75 folding device, a reciprocating feeding device for completing the movement of the article past the folding device, and means controlled by the movement of the article for moving the feeding device into operative 80 position, substantially as described.

12. The combination with a folding device for folding a covering sheet about an article, of means for advancing the article to the folding device, a reciprocating feeding device 85 for completing the movement of the article past the folding device, and means controlled by the pressure of the article for moving the feeding device into operative position, substantially as described.

13. The combination with folding devices for folding a covering sheet against opposite sides of an article, of means for advancing the article toward and between the folding devices, a reciprocating support, a pair of 95 pivoted feeding arms 102 carried by said support for completing the movement of the article between the folding devices, and means controlled by the pressure of the article for throwing said feeding arms into 100 position to engage the box, substantially as described.

14. The combination with folding devices for folding a covering sheet against opposite sides of an article, a presser bar 110 mounted 105 to move between the folding devices, means for supporting a covering sheet above the presser bar, means for feeding the article against the presser bar and between the folding devices, a reciprocating feeding device 110 for completing the movement of the article between the folding devices, and means whereby the movement of the presser bar causes a movement of the feeding devices into position to engage the article, substantially 115 as described.

15. The combination with folding devices for folding a covering sheet against opposite sides of an article, of a presser bar 110 mounted to move between the folding devices, a reciprocating support 104, pivoted feeding arms 102 carried by the support, and parts connected to the feeding arms adapted to be engaged by the presser bar for throwing the feeding arms into position to engage 125 the article, substantially as described.

16. The combination with folding devices for folding a covering sheet against opposite

- sides of an article, of a reciprocating support 104, a presser bar 110 carried by and mounted to reciprocate longitudinally of the support, a pivoted feeding arm 102 carried by 5 the support, a spring for holding the feeding arm normally in non-operative position, a part connected to the feeding arm and normally projecting into position to be engaged by the presser bar 110 when the latter is 10 moved toward the support and by the movement of which part the feeding arm is thrown into position to engage the article, and means for reciprocating the support to move the article between the folding devices 15 after the presser bar has been moved to throw the feeding arm into engaging position, substantially as described. 165
17. The combination with folding devices for folding a covering sheet against opposite 20 sides of an article, of a reciprocating support 104, a presser bar 110 carried by and mounted to reciprocate longitudinally of the support 104, a pivoted feeding arm 102 carried by the support, a part connected with the 25 feeding arm whereby the latter is thrown into engaging position by the movement of the presser bar toward the support, means for holding the presser bar in a normal position away from the support, means for reciprocating the support after the presser bar 30 has been moved toward the support to cause a movement of the feeding arm into engaging position, and means for returning the presser bar to its normal position with relation to the support, substantially as described. 35
18. The combination of the folding and pressing rolls 100, reciprocating grippers for moving covering sheets edgewise into position over the rolls 100, means for advancing 40 articles against the covering sheets and between the rolls 100, and a feeding device reciprocating below the line of movement of the grippers for completing the movement 45 of the article between the rolls 100, substantially as described. 460
19. The combination of the folding rolls 100 and the pressing rolls 101, reciprocating grippers for moving covering sheets edgewise into position over the folding rolls, means for advancing articles against the covering sheets and between the rolls, and a feeding device reciprocating below the line of movement of the grippers for completing the movement 55 of the article between the folding and pressing rolls, substantially as described. 555
20. The combination of the folding and pressing rolls 100, plunger 87 mounted to reciprocate toward and from the rolls 100, presser bar 110 mounted to reciprocate between the rolls 100, a feeding device for moving articles between the rolls, means controlled by the movement of the presser bar 60 for throwing the feeding device into operative position, and means for reciprocating the feeding device, substantially as described. 65
21. The combination with sheet applying mechanism for applying successive sheets to successive articles, of severing means for severing successive sheet lengths from a strip of material, feeding means for advancing sheet lengths of the strip past the severing means and for advancing the severed 70 sheet to the applying means, and a member for co-acting with registering devices on the strip for interrupting the movement of the strip when a sheet length has been moved past the severing means, substantially as described. 75
22. The combination with sheet applying mechanism for applying sheets to articles, of severing means for severing successive sheet lengths from a strip of material, pasting 80 means for applying paste to the sheet, feeding means comprising a surface gripper for engaging the pasted surface of the end of the strip, and means for actuating said gripper whereby the gripper is given an interrupted feeding movement to draw a sheet length of the strip past the severing means by the first part of its feeding movement and to advance the severed sheet to the applying means by the second part of its feeding 85 movement, and a stop member for engaging registering devices on the strip to hold the strip against movement by the gripper when a sheet length has been advanced beyond the severing means, substantially as described. 90
23. The combination with folding devices of means for applying paste to a strip of material, severing means, feeding means for drawing the end of the strip past the severing means and for advancing the severed 95 sheets to the folding devices, means for feeding a box edgewise against the strip and to the folding devices, and means for co-acting with registering devices on the strip for determining the length of the strip drawn past 100 the severing means before the operation of the severing means, substantially as described. 105
24. The combination of means for advancing a row of boxes flatwise of the boxes, means for moving the successive end boxes edgewise from the row, and means for giving the next box a slight backward movement to prevent injury to the boxes by the movement of the end box from the row, substantially as described. 110
25. The combination of means for advancing a row of boxes flatwise of the boxes, a plunger for pushing the successive end boxes edgewise from the row, and a rearward extension on the plunger having an inclined lower end for pushing the next box in the row slightly backward as the plunger moves 120
- 125

to push the end box from the row, substantially as described.

26. The combination of the holder 75 having side feeding belts 76 for frictionally engaging and advancing a row of articles in the holder, a stop against which the end article is moved when the row of articles is advanced by the feeding belts, and means for moving the successive end articles from the holder transversely to the direction of movement of the articles in the holder, substantially as described.

27. The combination of the holder 75 having side feeding belts 76 for frictionally engaging and advancing a row of articles in

the holder, means for moving the successive end articles from the holder transversely to the direction of movement of the articles in the holder, and means for forcing the next box slightly backward as the end box is moved from the holder, substantially as described.

In testimony whereof, I have hereunto set my hand, in the presence of two subscribing witnesses.

FRED R. HARRIS.
